UNITED STATES PATENT OFFICE.

MERRILL WATSON, OF EAST ORANGE, NEW JERSEY, AND HERBERT J. SMITH, OF NEW HAVEN, CONNECTICUT; JOHN H. WATSON, ADMINISTRATOR OF SAID MERRILL WATSON, DECEASED, ASSIGNEES TO AMERICAN FIBRE COOPERAGE COMPANY INC., OF DOVER, DELAWARE, A CORPORATION OF DELAWARE.

PAPER-BOARD BARREL.

Application filed August 22, 1922, Serial No. 533,552. Renewed October 30, 1923.

To all whom it may concern:

Be it known that we, MERRILL WATSON and HERBERT J. SMITH, citizens of the United States, and residents, respectively, of

5 East Orange, in the county of Essex and State of New Jersey, and New Haven, in the county of New Haven and State of Connecticut, have invented certain new and useful Improvements in Paper-Board Barrels; 10 and we do hereby declare the following to be a full, clear, and exact description of the invention, such as will enable others skilled in the art to which it appertains to make and use the same.

15 The invention relates to barrel staves formed of paperboard, and consists of certain improvements upon the stave forming the subject-matter of application Serial No. 523,306, which stave is preferably made up 20 of a series of plies of paperboard united by a suitable binder or adhesive, the latter serving to temporarily moisten the blank sufficiently to enable the same to be pressed into its ultimate form, which includes longitudinal and transverse curvatures and the 25 narrowing of the stave from the middle towards the ends. Such formation of the stave is effected by pressing the softened paperboard blank to impart the desired curvature thereto, and at the same time forming in the body of the blank an intermediate longitudinal groove which increases in depth and width from the center towards the ends, and transverse grooves near the ends intersecting the longitudinal groove, these several 30 grooves being made in the outer wall of the stave and therefore forming corresponding projections or ribs on the opposite or inner wall.

35 40 When the staves thus formed are made up into a barrel, the inwardly projecting ribs formed by the deepened end portions of the longitudinal groove overhang the barrel heads and lock them in place on the supporting ribs at the inner side of the stave formed by the outer transverse grooves. It 45 has been found in practice, however, that these locking ribs or projections must overhang the head at a fairly sharp angle in order to serve as an effective locking means, and in order to provide this it becomes necessary in some cases, for example, in the

smaller sizes of staves, to groove or depress the blank to an extent that tends to break or separate the fibre of the paperboard. This 55 obviously is objectionable and it has therefore been one of the objects of our present invention to improve the stave by avoiding the possibility of such breaking or separating of the fibre of the paperboard without otherwise substantially changing the desirable 60 characteristics of the stave. To this end our invention consists in the novel features of construction as hereinafter set forth in connection with the accompanying drawings, in 65 which—

Figure 1 is a perspective view of a suitable paperboard blank for forming a stave;

Fig. 2 is a plan view of a complete stave looking toward the inside;

Fig. 3 is an end elevation of the same;

Fig. 4 is a plan view of the stave from the outside;

Fig. 5 is a fragmentary sectional perspective view showing the mode of applying the 75 head and fastening hoops to the barrel,

Fig. 6 is a view of one of the barrel heads, and

Fig. 7 is a perspective view of the complete barrel.

Referring to the drawings, 1 indicates the paperboard blank for forming a single stave, the same preferably comprising a series of plies of rectangular sheets of paperboard, united by a suitable adhesive, such, for example, as silicate of soda, which will have the effect of first softening the blank to render the same more or less plastic and pliable, and subsequently to set or harden and retain the blank in the ultimate form 85 imparted thereto by the succeeding operations.

While the blank is still plastic or soft, due to the action of the adhesive, it is placed in a suitable press, which reduces 95 the blank to its final stave-like form, namely, with the proper bilge produced by imparting a longitudinal curvature from end to end and a transverse curvature from side to side. During the pressing operation 100 there is formed in the blank a median longitudinal groove 2, which increases in depth and width from the center of the blank toward each end, said groove comprising a

relatively narrow shallow middle portion and outwardly flaring deepening end sections 3 which have the effect of producing the necessary taper of the stave from the middle portion towards the ends. In addition to these grooves 2, there are also formed during the pressing operation a pair of parallel transverse grooves 4, 4, in the respective ends of the stave, all of which 5 grooves constitute material reenforcing or strengthening elements for each stave so that the staves may be handled and shipped without danger of breaking or deforming the same.

10 In the stave of the aforesaid application, one transverse groove only was provided at each end of the stave, this groove serving to receive the usual retaining hoop, and providing, at the inner side of the stave, an inwardly projecting ledge for the support 15 of the barrel head, the head being held or locked on this ledge by the overhanging end of the longitudinal rib. As hereinbefore referred to, this locking rib, to be 20 properly effective, should overhang the head at a fairly sharp angle, and to obtain this angle there must be formed the objectionable deep depression or groove in the paperboard as referred to, which is liable to result 25 in breakage of the fibre of the same. In the present case, we make the ends of the longitudinal grooves less deep to thereby avoid the possibility of such breakage. This of course lessens the effectiveness of 30 the rib formed by the groove as a locking means for the head. To make up for this we form the two transverse grooves 4, 4, in the respective ends of the stave to receive the fastening hoops 5, 5, and space these 35 grooves so as to form at the inner side of the stave and at opposite sides of the longitudinal rib 6, aligned channels 7, 7, to receive the head 8, the latter being firmly held in said channel seats and against movement endwise of the staves by the fastening 40 hoops 5, 5, positioned directly above and below the same.

The end of the rib 6 in the present case, notwithstanding its reduced angle of overhang above the head as compared with that 45 of the rib of the aforesaid application, serves to supplement the channel seats 7, 7, as a means for holding the head in place.

The head 8, as shown in Figs. 6 and 7, is 50 formed with spaced indentations 9 in its peripheral edge to receive the ribs 6 at the inner side of the staves.

In the particular formation and struc-

tural arrangement of the stave as illustrated, eight units are sufficient to form a 60 barrel, and when assembled in the usual manner and the heads and fastening hoops applied, a very strong and light barrel, as illustrated in Fig. 7 results.

What we claim is:—

1. A barrel stave comprising a blank of paperboard having a longitudinal groove in its outer wall forming a corresponding rib on its inner wall, and a pair of transverse grooves in its outer wall near each end 70 forming aligned channels in its inner wall at opposite sides of the rib thereon.

2. A barrel stave comprising a blank of paperboard having a longitudinal groove in its outer wall increasing in depth and 75 width from the center towards each end of the blank and forming a corresponding rib at the inner side of the latter, and a pair of transverse grooves in its outer wall near each end forming aligned channels in its 80 inner wall at opposite sides of the rib thereon.

3. A barrel comprising a plurality of adjoining staves, each formed of a blank of paperboard having a longitudinal groove in 85 its outer wall forming a corresponding rib on its inner wall, and also having a pair of transverse grooves in its outer wall near each and forming aligned channels in its inner wall at opposite sides of the rib 90 thereon, heads seated in the channels of the adjoining staves and having indentations to receive the ribs of the staves, and retaining hoops seated in the transverse grooves in the outer walls of the staves.

4. A barrel comprising a plurality of adjoining staves, each formed of a blank of paperboard having a longitudinal groove in its outer wall increasing in depth and width from the center towards each end of the 100 blank and forming a corresponding rib at the inner side of the latter, and also having a pair of transverse grooves in its outer wall near each end forming aligned channels in its inner wall at opposite sides of 105 the rib thereon, heads seated in the channels of the adjoining staves and having indentations to receive the ribs of the staves, and retaining hoops seated in the transverse grooves in the outer walls of the 110 staves.

In testimony whereof we affix our signatures.

MERRILL WATSON.
HERBERT J. SMITH.
